METAL CONTAINER

Edwin G. Gaynor, Fairfield, Conn.

Application June 22, 1940, Serial No. 341,915

5 Claims. (Cl. 220—67)

This invention relates to new and useful improvements in metal containers and has particular relation to a metal housing or container for an electricity valve used with a fluorescent lamp and which container is adapted to fit in the cable raceways used in electrical wiring.

The objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is a side elevational view showing a container made in accordance with the invention;

Fig. 2 is a transverse sectional view taken as along the line 2—2 of Fig. 1;

Fig. 3 is a plan view showing the blank from which an end of the container is formed;

Fig. 4 is a view showing the manner of applying either end to the container; and

Fig. 5 is a detailed sectional view.

Referring in detail to the drawing, the container of the invention comprises an elongated tubular body 10 which, as shown in Fig. 2, is substantially rectangular with its corners rounded and is also somewhat elongated in transverse section. This container is constructed to be received in the usual cable raceway used in electrical wiring and as such raceways are of limited dimensions, a container of minimum cross-section is necessary.

The body 10 is formed from a single piece of sheet metal bent or rolled to the proper shape and the longitudinal edges 11 and 12 are brought into substantially abutting relation forming a seam 13 extending longitudinally of the body along one of the narrow edges thereof and serving to prevent the circulation of eddy currents about the girth of the body. Adjacent each end the body is pierced to provide each of its end portions with similarly located openings.

A pair of such openings are designated 14 and 15 and they are located adjacent to and equidistant from the edges 11 and 12 respectively. An opening 16 is located approximately 90 degrees from the openings 14 and 15 and is in a side wall 17 of the container preferably approximately 17 midway the edges of such wall. Yet another opening 18 is found in the side wall 19 and as shown, is located substantially opposite the open-

ing 16 and approximately 270 degrees with respect to the openings 14 and 15.

The ends of the body 10 are closed by removable ends or end plates 20 and 21 respectively.

5 Each such end is formed from a blank such as is shown in Fig. 3 and the same includes a plate-like portion 22 of a size and shape to substantially close an end of the body 10 and carrying an ear or mounting means to be used in securing the container to a base or support. The ear 23 is kerfed as at 24 for the passage of securing means and the end plate 22 is provided on one transverse edge with a pair of lugs 25 and 26 and on one longitudinal edge with a lug 27 and on the opposite longitudinal edge and substantially opposite to the lug 27 with a lug 28.

When the ends 20 and 21 are in place, it will be clear that the mounting portions or ears 23 of the respective ends have been bent along the dotted line 29 of Fig. 3 in opposite directions in order to form the ends for proper location in the respective end portions of the container. In the assembly the lugs 25 and 26 are disposed in the openings 14 and 15. The lug 28 is disposed in the opening 16 and the lug 27 is disposed in the opening 18.

Since the plate-like portion 22 of an end is of a size and shape substantially equal to the inside of the body 10, it will be apparent that when the lugs are in the openings as described, the respective ends are securely attached to the container and close the end portions of the same. The mounting portions or ears of the ends 20 and 21 project beyond the ends of the container body 10 and preferably are slightly offset as at 30 (see Fig. 5) whereby the kerfed portions of such ears are substantially in alignment with the rear wall 19 of the container and will thus lie flat against any holder or support to which the container is attached. Terminal or lead openings 31 are provided in the plate-like portions 22 of the ends.

With the construction described, the ends 20 and 21 are easily inserted in place and are easily removable therefrom. Fig. 4 suggests the manner in which the ends are applied or inserted and there it will be noted that the lugs 25 and 26 are in the openings 14 and 15 and that the lug 28 is in the opening 16. However, since the plate 22 is of a contour similar in shape and dimensions to the inside of the body 10, the lug 27 is against the end edge of the wall 19 of the body. The end 21 is applied to the extent indicated in Fig. 4 simply by grasping the ear 23 and simultaneously inserting the lugs 25, 26, and 28

into the proper openings. Thereafter a small screw driver or the like is used as a pry and inserted over the ear 23 and under the wall 19 to spring the latter out a bit and permit of the lug 27 passing under said wall into alignment with the opening 18.

On withdrawal of the pry, the container springs back to shape so that the lug 18 is located in the opening 27. Should occasion require that the end be at any time removed, wall 19 is again pried or sprung outwardly to free the lug 27 from the opening 18 whereupon on pulling the ear 23, the entire end may be removed from the container.

It will be apparent that owing to the size and contour of the plate 22 with respect to the inner dimensions of the body, the spring-like action of the body will retain the plate in position since it maintains the lugs in the respective openings. The pair of lugs 25 and 26 being located at opposite sides of the seam 23, serve mechanically to secure the body 10 together by preventing opening of said seam. Ears 23 are used when applying or removing the ends 20 and 21 as well as serving as a means for the mounting of the container. From the above it will be clear that I have provided a simple and inexpensive structure particularly suited for the use intended.

Having thus set forth the nature of my invention, what I claim is:

1. In a metal container of the class described, a tubular body of a cross-sectional configuration and size to be received in the usual cable raceways used in electrical wiring, said body comprising a piece of metal having its ends arranged in substantially abutting relation forming a seam along one wall of the body, said body having a pair of openings through said wall near an end and adjacent to and equidistant from the respective edges of said seam, said body having other openings in its sides near said end and spaced approximately 90 and 270 degrees respectively from said seam, an end in said container comprising a metal plate of a contour and size substantially the same as that of the inside of the body, lugs on said end disposed in all of said openings, said lugs in the openings at the respective edges of the seam maintaining the seam fixed, and a mounting ear on said end and projecting beyond the container.

2. In a metal container of the class described, a tubular transversely rectangular body of a cross-sectional configuration and size to be received in the usual cable raceways used in electrical wiring, said body comprising a piece of metal having its edges arranged in substantially abutting relation forming a seam along one side of the body, said body having a pair of openings near its end and located one immediately at each side of said seam, said body having openings in each of two other of its side walls, and end in said container and comprising a metal plate of a contour and size similar to that of the inside of the body, lugs on the edges of said plate and disposed one in each of said openings, said lugs

in the openings at the respective edges of the seam maintaining the seam fixed, and a mounting ear on said end and projecting beyond the container.

5. In a metal container of the class described, a tubular transversely elongated body of a cross-sectional configuration and size to be received in the usual cable raceways used in electrical wiring, said body having an open seam in one

10 of its edge walls, said body having a pair of openings through said edge wall near an end of the body and located one at each side of said seam, said body having openings in each of two other of its side walls, an end in said container and comprising a metal plate of a contour and size similar to that of the inside of the body, lugs on the edges of said plate and disposed one in each of said openings, said lugs in the openings at the respective edges of the seam maintaining the seam fixed, and a mounting ear on said end and projecting beyond the container.

20 4. In a metal container of the class described, a tubular transverse elongated body of a cross-sectional configuration and size to be received

25 in the usual cable raceways used in electrical wiring, said body having an open seam in one of its edge walls, said body having a pair of openings through said edge wall near an end of the body and located one at each side of said seam, said body having openings in each of two other of its side walls, an end in said container and comprising a metal plate of a contour and size similar to that of the inside of the body, lugs on the edges of said plate and disposed one in each of said openings, said lugs in the openings at the respective edges of the seam maintaining the seam fixed, and a mounting ear on said end and projecting beyond the container.

30 3. In a metal container of the class described, a tubular body of a cross-sectional configuration and size to be received in the usual cable raceways used in electrical wiring, said body having an open seam in one of its edge walls, said body having a pair of openings through said edge wall near an end of the body and located one at each side of said seam, said body having openings in its opposite side walls near said end, an end in said container and of a contour and size similar to that of the inside of the container, lugs on said end and disposed one in each of said openings, said

35 lugs in the openings at the respective edges of the seam maintaining the seam fixed, and a mounting ear on said end and projecting beyond the container.

4. In a metal container of the class described, 40 a tubular body of a cross-sectional configuration and size to be received in the usual cable raceways used in electrical wiring, said body comprising a piece of metal having its ends arranged in substantially abutting relation forming a seam along one wall of the body, said body having a pair of openings through said wall near an end and adjacent to and equidistant from the respective edges of said seam, said body having other openings in its sides near said end and spaced approximately 90 and 270 degrees respectively from said seam, an end in said container comprising a metal plate of a contour and size substantially the same as that of the inside of the body, lugs on said end disposed in all of said openings, said lugs in the openings at the respective edges of the seam maintaining the seam fixed, and a mounting ear on said end and projecting beyond the container.

45 5. In a metal container of the class described, a tubular body of a cross-sectional configuration and size to be received in the usual cable raceways used in electrical wiring, said body comprising a piece of metal having its ends arranged in substantially abutting relation forming a seam along one wall of the body, said body having a pair of openings through said wall near an end and adjacent to and equidistant from the respective edges of said seam, said body having other openings in its sides near said end and spaced approximately 90 and 270 degrees respectively from said seam, an end in said container and comprising a metal plate of a contour and size substantially the same as that of the inside of the body and having lugs disposed in all of said openings, said lugs in the openings at the respective edges of the seam maintaining the seam fixed, a mounting ear on said end and projecting beyond the container, and said container adapted to spring whereby a wall thereof

50 55 may be forced outwardly to permit said end to be disposed in the container with said lugs in the openings and thereafter on release of said wall spring back to normal position to secure said end in position with its lugs in said openings.

EDWIN G. GAYNOR.
